U.S. Cl. Plt.—79

1 Claim

The present invention comprises a new and distinct cultivar of chrysanthemum plant which is a sport of the 10 cultivar known in the United States as Belair, which forms the subject matter of pending U.S. plant patent application Ser. No. 58,750, filed July 27, 1970, and now P.P. 3,184.

The new cultivar is similar in many respects to Golden Belair, which is disclosed and illustrated in pending U.S. application Ser. No. 58,751, filed July 27, 1970, and now P.P. 3,185, having the same characteristics as Golden Belair of:

- (1) Flower size.
- (2) Same recommended period of flowering.
- (3) Foliage size and color.

The new cultivar is distinguished from Golden Belair by the following characteristics, when grown under comparable conditions:

- (1) A more intense flower color.
- (2) The flower color under high light and temperature conditions is a truer bronze rather than a golden bronze or yellow.
- (3) A higher flower crown and more formal flower form.
- (4) Three to four days earlier response.
- (5) A more uniform response within a flowering plot.
- (6) 2" shorter habit.

The new cultivar is also similar in many respects to 35 Bronze Belair, which is illustrated and described in pending U.S. application Ser. No. 58,749, filed July 27, 1970, and now P.P. 3,183, having the same characteristics as Bronze Belair of:

Botanical classification: *Chrysanthemum morifolium*

	Flame Belair	Golden Belair	Bronze Belair
Bloom:			
Size:	3"	3"	2½"
Fully expanded:	3½"	3½"	3"
Borne:	Terminal cluster of 8-12 on elongated pedicels according to culture.		
Stems:	Elongated pedicels.		
Form:	Decorative.		
permanence:	7-10 days.		
Color:			
Center of flower	Orange bronze, 5YR6/12.	Orange yellow, 8.75YR6/12 to 7.5YR7/12.	Orange bronze, 2.5YR5/10 to light bronze, 10YR8/10.
Base of petals	Yellow 5Y8.5/12.	Yellow 3.75Y8/12.	Bronze, 2.5YR5/10.
Inside of petals	Orange to bronze, 1.25YR5/12 to 8.75YR6/12.	Yellow, 2.5Y8/10 to yellow, 1.25YR8/14.	Bronze, 2.5YR5/10 to light bronze, 10YR8/10.
Reverse of petals	Gold to yellow, 1.25Y7/12 to 5Y8/10.	Yellow, 2.5Y8.5/10.	Light yellow, 2.5Y8.5/6.
Tonality from a distance	Orange bronze.	Golden bronze.	Orange bronze to light bronze.
Discoloration	Orange bronze, 1.25YR5/12.	Yellow, 1.25YR8/14.	Light bronze, 10YR8/10.
Petals:			
Texture	Smooth.	Smooth.	Smooth.
Appearance and form	Slightly open at base, broadens quickly to flat keel, tapering to a blunt point with recurved edges.	Slightly open at base, keeled at mid point, tapering to a blunt point.	Slightly open at base, keeled at mid point, tapering to a blunt point.
Arrangement	Composite, whorled on a single receptacle.		
Persistence	Resist shatter.		
Fragrance	Typical chrysanthemum.		
Reproductive organs:			
Stamen, anthers	None to 20, more or less depending on culture.		
Pollen	None to scant.		
Arrangement	Clustered in center of flower, if present.		
Styles	Present in both ray and disc florets.		
Length	Short.		
Ovaries	At the base of petal attached to receptacle.		
Plant:			
Form	Herbaceous.		
Growth	Upright.		
Height	Approximately 36"-42" when given 1 to 3 long day weeks and a total crop time of 10 to 12 weeks for the various recommended seasons of the year as defined in the timetables of Yoder Bros., Inc., Barberton, Ohio.	Approximately 38"-44" when given 1 to 3 long day weeks and a total crop time of 10 to 12 weeks for the various recommended seasons of the year as defined in the timetables of Yoder Bros., Inc., Barberton, Ohio.	Approximately 36"-42" when given 1 to 3 long day weeks and a total crop time of 10 to 12 weeks for the various recommended seasons of the year as defined in the timetables of Yoder Bros., Inc., Barberton, Ohio.

TABLE—Continued

	Flame Belair	Golden Belair	Bronze Belair
Spread	None when grown single stem to little when pinched.		
Foliation:			
Top side	Dark green, 7.5G Y3/4		
Size	7"-9" long, 4"-5" wide		
Quantity	Numerous		
Shape	Spatulate lobed		
Texture	Coarse		
Ribs and veins	Prominent		
Edge	Deeply indented		
Serration	Slight		
Under side	Light green, 7.5G Y4/4		
Stipules	Prominent at base of petiole		

We claim:

1. A new and distinct cultivar of *crysanthemum* characterized particularly as to its uniqueness when compared to the cultivar *Golden Belair* by its more intense bronze flower color, particularly under high light and temperature conditions, higher flower crown and more formal flower form, three to four days earlier and more uniform response, and its 2 inch shorter habit; and characterized as

15 to uniqueness when compared to the cultivar *Bronze Belair* by its more intense bronze color and better color retention under high light and high temperature conditions and during maturity of flower.
